DESIGN FOR A STAPLING DEVICE

William G. Pankonin, Chicago, Ill.

Application May 21, 1934, Serial No. 51,864

Term of patent 14 years

To all whom it may concern:

Be it known that I, WILLIAM G. PANKONIN, a citizen of the United States, residing at Chicago, county of Cook, and State of Illinois, have invented a new, original, and ornamental Design for a Stapling Device, of which the following is a specification, reference being had to the accompanying drawing, forming a part thereof.

Figure 1 is a perspective view from the rear of a stapling device showing my new design; and Figure 2 is a side elevation on a reduced scale of the stapling machine shown in Figure 1.

I claim:

The ornamental design for a stapling device as shown.

WILLIAM G. PANKONIN.
